UNITED STATES PATENT OFFICE

ALFRED L. EUSTICE, OF CHICAGO, ILLINOIS

FUSE

Application filed December 1, 1921. Serial No. 519,159.

The present invention relates to fuses.

The present invention has been illustrated herein in connection with a plug fuse and, as will appear hereinafter, has decided advantages in a fuse of this type, though, in its broader aspects, the present invention has a wider field of applicability than plug fuses.

An object of the present invention is to provide a fuse which has a great uniformity of 10 operation.

A further object is to provide a fuse of the plug type in which the fusible element will "blow" at a predetermined point which is plainly visible, thereby doing away with the 15 uncertainty as to whether or not a fuse is in operative condition.

A further object is to provide a fuse of the plug type which is very simple to manufacture and which therefore adapts itself 20 readily to quantity production on a commercial basis.

Further objects will appear as the description proceeds.

Referring to drawings, 25 Figure 1 is an end view illustrating one embodiment of the present invention.

Figure 2 is an end view of the embodiment illustrated in Figure 1, but taken from the opposite end of the fuse.

30 Figure 3 is a transverse sectional view.

Figure 4 is a view illustrating the fusible element independently of its co-operative parts.

35 Figures 5 and 6 are views in perspective illustrating the two sides of one of the parts of the fuse.

Figure 7 is a contact member used in the improved fuse.

40 Figure 8 is a view illustrating the manner of constructing the fusible element.

As perhaps best illustrated in Figure 3, the fuse according to the present invention comprises a pair of holding members 10 and 11 which should be of insulating material 45 capable of being molded, such as hard rubber. Member 10 comprises a cylindrical member which may be provided with screw-threads 12 for a purpose which will be apparent hereinafter. The member 11 comprises a cap member adapted to abut one end

of the cylindrical member 10. The cap member 11 is held in fixed relation with the cylindrical member 10 by means of the shell or casing 13, which may be of relatively thin conducting material, swaged to form screw-threads 14—14 co-operating with the screw-threads 12—12. The shell 13 will also have a turned over end portion 15 for engaging the outer side of the cap 11.

55 Mounted centrally of the cap 11 is the contact member 16, provided with the head 17 and the shank 18, which shank lies axially of cylindrical member 10. The fusible element, which is indicated by the numeral 19, is provided with a hole 20 for the reception of the shank 18 of the contact member 16. Said 60 fusible element 19 is bent intermediate of its length in a plurality of places whereby to fit within the chamber formed by the cylindrical member 10. The shank 18 of the contact member 16 may be upset after the fusible element has been mounted thereon, and a rigid connection between said fusible element and said shank 18 may be ensured by soldering 65 said members together. The contact 70 member 18 should be firmly held within the cap 11 between the abutments formed by the head 17 and the end of the fusible element 19. Rotating movement of the contact member 16 may be prevented by the construction illustrated, comprising a lug 21 on the head 17, which lug fits within the corresponding recess 22 in the cap member 11. In order to 75 properly hold the cap member 11 in proper position relative to the cylindrical member 80 10, said cap member may be provided with an outstanding lug 23 adapted to fit more or less closely within a corresponding recess in the co-operating end of cylindrical member 10. By reason of the fitting of lug 23 within its 85 corresponding recess, the cap member will be stopped as regards any tendency toward rotation, whereby the fusible element will always be held in its proper position within the cylindrical member 10.

85 As indicated in Figures 3 and 4, the fusible element 19 comprises the end portion 24 lying in proximity to the cap 11. Said fusible element is provided with a portion 25 lying in a 90 position along the inner wall of the cylind-

drical member 10 and has another portion 26 lying substantially normal to the axis of the cylindrical member 10. Another portion 27 of the fusible element lies in proximity to the inner wall of the cylindrical member 10, being spaced from the member 25, and extending to a point adjacent to the plane of the end portion 24. Fusible element 19 has a portion 28 which may overlie the end of the cylindrical member 10, being located within a slot in said end, whereby the outer side of the fusible member 19 will lie approximately in the same plane as the end of cylindrical member 10.

15 Fusible element 19 is provided with still another bent-over portion 29 adapted to lie in a corresponding slot on the outside of cylindrical member 10. The portion 29 of the fusible element 19 may have its outer surface 20 engaged by the threaded shell or casing 13.

It will be evident without detailed description that when the cap member 11, with the fusible element mounted thereon, is applied to the left-hand end of the cylindrical member 10, as viewed in Figure 3, said members may be held in fixed relation by means of the screw-threaded shell 13. The shell 13 will have a good electrical connection with the end portion 29 of the fusible element 19 by 25 reason of the contact of the screw-threads 14-14 of said shell with said end portion 29. In order to further ensure a perfect contact, said shell member 13 may be soldered to the end portion 29 of the fusible element 19, as 30 indicated by the numeral 30, (Figure 3).

The right-hand end of the cylindrical member 10 is provided with an enlarged grip portion 31 by means of which the plug fuse may be readily manipulated. Said right-hand end of the plug fuse is provided with a sight opening 32 which may be provided with a mica, glass or other transparent closure 33. Said closure 33 may be held in place by any preferred means, which means need 40 not be described herein inasmuch as they are well known and constitute no part of the present invention.

The fusible element 19 is provided, at a point clearly visible through the sight opening 32, with a pair of opposed notches providing a restricted portion 34. Experimentation and practical demonstration have shown that the number of restricted portions in a fusible element should preferably be an odd number. According to the present invention, three restricted portions are illustrated, one of which lies in the portion 25 of the fusible link and the other of which lies in the portion 27 of the fusible link, both of said restricted 55 portions being indicated by the numeral 35. The restricted portions 35-35 should preferably be located substantially symmetrically with respect to the restricted portion 34. Said restricted portion 34 may, with advantage, be located substantially midway be-

tween the two terminals of the fusible element. The restricted portions 35-35 and 34 may be of substantially the same dimensions, or portion 34 may present less metal than does either of the portions 35. The reason for this construction need not be discussed herein, but it may be stated briefly that the center restricted portion 34 will melt and break the circuit, either on slight overload beyond the capacity of the fuse, or upon very heavy overload, such as accompanies a short circuit. The restricted portions 35-35, flanking the restricted portion 34, ensure the melting of the center restricted portion in all cases in which it is required that the fusible element should melt. The restricted portion 34 is located directly in front of the sight opening and in close proximity thereto, and inasmuch as the fuse will invariably melt at this point, there is no reason for uncertainty as to whether or not a fuse has "blown". The term "in front of the sight opening", as apparent from the drawing, refers to a position inwardly of the fuse relative to the sight opening. In other words, the term "front" as used in this connection refers to a position toward the head 17 of the fuse.

For convenience in assembling on a quantity basis, each of the elements of the fuse should be provided with locating means whereby the fuses will invariably be put together in the same relation. For this purpose, and for a further purpose which will be stated shortly, the cap member 11 is provided with holes 36-36. The right-hand end cylindrical member 13 may be provided with a locating hole 37. The non-cylindrical parts of the fuse will provide their own locating means. The fusible element 19 will preferably be bent into the required shape by machinery. Furthermore, the contact member 16 will be inserted within the cap member 11, with the lug 21 fitting within recess 22, and the fusible element will be attached by machinery. The cap member 11 will then be applied to the cylindrical member 10, the proper angular relation in the machinery being ensured by the locating holes 36-36 and 37. Engagement of lug 23 will prevent turning of cap member 11 relative to cylindrical member 10 while the machinery is turning up the threaded shell 13. Thereafter the machinery will swage the turned over portion 15 of shell 13, whereby parts thereof will lie within the holes 36-36 of the cap member 11 to hold the shell member 13 against rotation.

In order to improve the visibility of the fusible element 19, that portion of said fusible element which is visible through the sight opening 32 may be painted a light color, or may be painted with luminous paint. This expedient is of importance, inasmuch as fuses are frequently located in very dark closets or corners. In making the fusible elements, said

elements may be struck from a blank such as illustrated in Figure 8. Said blank, which is indicated by the numeral 38, may be provided with a band of luminous or other highly visible paint intermediate of its width. Figures may be stamped on a visible portion of the fusible element indicating the capacity of the fuse in amperes. The fuse elements may be struck from a blank 38 and bent into the form shown in Figure 4, in which case the restricted portion 34, with the luminous paint covering that region of the fusible element, will lie in a position to be visible through the sight opening 32 of the fuse.

I do not desire to have the scope of my invention limited to plug fuses, inasmuch as the advantages of the present invention are applicable to other types of fuses. One embodiment of the present invention has been described in detail. Many modifications will occur to those skilled in the art. It is intended in this patent to cover all such modifications that fall within the scope of the invention as defined by the appended claims.

I claim:

1. An electric fuse comprising a substantially closed receptacle having a sight opening and a fusible element mounted within said receptacle, said fusible element having a plural odd number of restricted portions, the central one of which is located substantially symmetrically with the remainder of said restricted portions, said central restricted portion being located directly in front of said sight opening to be readily visible through said sight opening.

2. An electric fuse comprising a receptacle providing a substantially closed chamber, a cap for said chamber, and a fusible element arranged along the walls of said chamber, said fusible element having a plural odd number of restricted portions, said chamber having a sight opening, the central one of said restricted portion being positioned directly in front of said sight opening to be readily visible through said sight opening.

3. An electric fuse comprising a cylindrical member, a cap member for one end of said cylindrical member, a contact member located centrally of said cap member, said contact member having a head portion and an upset shank portion, threaded conducting means providing an electrical terminal and uniting said cylindrical member and said cap member, and a fusible element connected to said contact member by means of said upset shank portion and also being connected to said threaded means, said cap member being provided with a plurality of holes suitable for locating said cap member relative to said cylinder member in assembling, said conducting means being swaged into said holes to prevent rotation of said metallic conducting member.

4. An electric fuse comprising a cylindrical

member, a cap member for one end of said cylindrical member, a contact member located centrally of said cap member, said contact member having a head portion and an upset shank portion, threaded conducting means 70 providing an electric terminal, and uniting said cylindrical member and said cap member, and a fusible element connected to said contact member by means of said upset shank portion, and also being connected to said threaded means, said cap member being provided with a plurality of holes suitable for locating said cap member relative to said cylinder member in assembling, said conducting means being swaged into said holes to 80 prevent rotation of said metallic conducting member, said cylindrical member being provided with a sight opening, said fusible element being provided with a restricted portion visible through said sight opening.

5. An electric fuse comprising a cylindrical member, a cap member for one end thereof, and a metallic member having screw-threaded engagement with said cylindrical member for holding said cap member in proper relation to said cylindrical member, said cap member being provided with a plurality of holes on the outer side thereof suitable for locating said cap member relative to said cylindrical member in assembling, said metallic conducting member being swaged into said holes to prevent rotation of said metallic conducting member.

6. An electric fuse comprising a chamber having a sight opening, a fusible element 100 mounted within said chamber and having electrical connection at each end thereof with the exterior of said chamber, said fusible element having a restricted portion substantially midway between said exterior electrical connections, the region of said fusible element adjacent to said restricted portion being covered with paint of high visibility, said restricted portion being located in a position to be visible through said sight opening.

7. An electric fuse comprising a chamber having a sight opening, a fusible element located within said chamber and having an electrical connection at each end thereof with the exterior of said chamber, said fusible element 115 having an odd number of restricted portions, of which the central restricted portion is symmetrically arranged relative to the other restricted portions, said central restricted portion being located in a position to be visible 120 through said sight opening, the region of said fusible element adjacent to said central restricted portion being covered with paint of high visibility.

8. An electric fuse comprising a receptacle having a sight opening and a fusible element mounted within said receptacle, said fusible element having an odd number of restricted portions, the central one of which is located substantially symmetrically with the re- 125

- 5 remainder of said restricted portions, said central restricted portion being located in a position to be visible through said sight opening, said fusible element being covered, in the region of said central restricted portion, with paint of high visibility.
- 10 9. A fuse plug of the window type provided with a current carrying fusible element having a luminescent portion located to be viewed through the plug window.
- 15 10. A fuse plug of the window type provided with a current carrying fusible element having a luminescent and fusible portion located to be viewed through the plug window.
- 20 11. A fuse plug of the window type provided with a current carrying fusible element having luminous paint applied to a surface thereof visible through the plug window.
- 25 12. A fuse plug of the window type provided with a current carrying fusible element of an elongated form and having luminous paint applied to a fusible portion thereof visible through the plug window.
- 30 13. An electric fuse comprising a substantially closed receptacle having a sight opening and a fusible element mounted within said receptacle, said fusible element having a plural odd number of restricted portions, the central one of which is located in a position in close proximity to said sight opening and directly in front of said sight opening.
- 35 14. An electric fuse comprising a substantially closed receptacle having a sight opening and a fusible element mounted within said receptacle, said fusible element having a plural odd number of restricted portions, the central one of which is located substantially symmetrical with the remainder of said restricted portions, said central restricted portion being located in a position directly in front of said sight opening and in close proximity to said sight opening.
- 40 15. An electric fuse comprising a substantially closed receptacle having a sight opening and a fusible element mounted within said receptacle, said fusible element having a plural odd number of restricted portions, the central one of which is located in a position in close proximity to said sight opening and directly in front of said sight opening, said restricted portions having substantially the same dimensions.
- 45 16. An electric fuse comprising a substantially closed receptacle having a sight opening and a fusible element mounted within said receptacle, said fusible element having a plural odd number of restricted portions, the central one of which is located substantially symmetrical with the remainder of said restricted portions, said central restricted portion being located in a position directly in front of said sight opening and in close proximity to said sight opening, said restricted portions having substantially the same dimensions.
- 50 17. An electric fuse comprising a substantially closed receptacle having a sight opening and a fusible element mounted within said receptacle, said fusible element having a plural odd number of restricted portions, the central one of which is located substantially symmetrical with the remainder of said restricted portions, said central restricted portion being located in a position directly in front of said sight opening and in close proximity to said sight opening, the central restricted portion presenting no more metal than do the other restricted portions, said other restricted portions having substantially the same dimensions.
